CAN OPENING KEY

George P. Ziehmer, Jr., New York, N. Y., assignor
to American Can Company, New York, N. Y., a
corporation of New Jersey.

Application August 31, 1943, Serial No. 500,700.

4 Claims. (Cl. 220—52).

1

The present invention relates to tearing strip cans and more particularly to a welded break-off key and a method of making the same, for opening such cans by removing the tearing strip.

An object of the invention is the provision of a key having a novel form of welding lugs which provide for easy welding and which firmly secure the key to the can cover, such welding lugs being formed from the metal of the key adjacent or contiguous the slot, thus eliminating the necessity of providing extra operations or extra metal to form the lugs and thereby reducing the cost of the key.

Still another object of the invention is the provision of a method of manufacturing such a key utilizing simple die operations.

Numerous other objects and advantages of the invention will be apparent as it is better understood from the following description, which, taken in connection with the accompanying drawings, discloses a preferred embodiment thereof.

Referring to the drawings:

Figure 1 is a perspective view of the upper portion of a tearing strip can having a key embodying the present invention attached thereto.

Fig. 2 is an enlarged longitudinal section taken substantially along the line 2—2 in Fig. 1, with parts broken away.

Fig. 3 is a transverse section taken substantially along the line 3—3 in Fig. 2.

Fig. 4 is a sectional view similar to Fig. 3 taken substantially along the line 4—4 in Fig. 2.

Fig. 5 is a top plan view of the portion of the key shown in Fig. 2.

Fig. 6 is a sectional view similar to Fig. 2 and showing the key (with parts broken away) immediately after it has been broken away from the can.

Fig. 7 is a longitudinal section taken through one form of apparatus for forming the key and illustrating the first step in the manufacture of the key, with parts broken away.

Fig. 8 is a transverse section taken substantially along the line 8—8 in Fig. 7, with parts broken away.

Fig. 9 is a longitudinal section similar to Fig. 7 and illustrating the final step in the manufacture of the key, with parts broken away.

Fig. 10 is a transverse section taken substantially along the line 10—10 in Fig. 9, with parts broken away.

As a preferred embodiment of the invention, the drawings disclose a sheet metal can body 11 having a side seam 12. The body 11 is provided at its upper portion with a pair of spaced and

parallel score lines 13, 14 defining a tearing strip 15, one end of which terminates in a free tongue 16 which extends beyond the side seam 12. A top end member 17, also formed of sheet metal is secured to the body 11, preferably in a conventional double seam 18. This type of can is opened in the usual manner by the removal of the tearing strip 15 with a slotted key 19 which is preferably spot welded to the top end member 17 to temporarily hold it in place on the can during shipment and storage.

The key 19 is formed preferably from a suitable piece of round metal wire providing a stem or shank 21. One end of the shank is bent into a loop handle 22. The opposite end of the shank is formed with a flat section 23.

The flat section 23 of the key is formed with an oblong depression or recess 24 which extends down into the metal of the key for nearly its full thickness, leaving a relatively thin bottom wall 25. This bottom wall is pierced to provide an elongated slot 26 adapted to receive the tongue 16 of the can, when the can is to be opened.

The bottom wall 25 is further provided with two welding projections or teats 27, 28 which are located one at each end of the slot and which extend outwardly beyond or below the key as best shown in Fig. 2. The key is secured to the can cover, preferably by spot welding through the projections to hold it on the can for shipment and storage, as hereinbefore mentioned. As a precautionary measure, it is desirable to use a welding electrode shaped to fit into the key depression 24 during the welding operation so that it will bear directly onto the welding projections to prevent shearing them off.

The welding projections 27, 28 preferably are square in cross-section and of substantially the same width as the slot 26 so that they may be readily formed from metal ordinarily cut out of the key when it is pierced to provide the slot. The projections therefore are integral parts of the key and extend from the key in relatively thin neck portions or sections 31 of metal which may be equal to the thickness of the bottom wall 25 or may be thinner if desired. The necks of the teats or projections may be readily broken in removing the key from the can cover for use, as will be more fully explained at this time.

To break off the key from the can for use in removal of the tearing strip it is merely necessary to lift the handle part 22 away from the can cover 11. This section first ruptures the thin neck 31 of the innermost projection 27 and second, breaks away the neck of the outer projection 28.

These breaks take place transversely of the bottom wall 25 and thus elongate slightly the slot 26 in the key. This frees or releases the key from the can cover. The projections remain attached to the can cover. The necks 31 of the projections should be of the proper thinness so that they will easily break and so that undue force will not be required to lift the key handle. At the same time when properly made these necks will hold the key securely in place on the can until it is needed for removal of the tearing strip in opening the can.

In some cases two or more welding projections may not be required for holding the key in place on the can. If desired one projection may be used and this may be located at either end of the slot 26 or may be disposed intermediate its ends. In any case it is desirable to have the projection or projections of a width substantially that of the slot in order that the connection may constitute an easily rupturable neck or necks. Furthermore, such construction permits the necks being struck out of the metal usually cut away from the key to provide the slot 26.

Figures 7 to 10 illustrate principal parts of a die mechanism for carrying out the steps of the method of making the key from a key blank having the loop handle 22 and the flat shank section 23 already formed therein. In such a method of making keys, the depression 24 and the welding projections 27, 28 are simultaneously formed in the key blank. The slot 26 is then pierced in the bottom wall of the depression and this leaves the welding projections in the proper location and in proper condition for the purposes hereinbefore mentioned.

Forming of the depression 24 and the initial step of forming the welding projections 27, 28 are brought about preferably in a die mechanism including a lower die block 34 (Figs. 7 and 8), 40 which may be stationary, and a cooperating movable upper forming punch 35. The die block is formed with a flat top surface 36 for the reception of the flat section 23 of a key blank and has an elongated, narrow, slot opening 37 of substantially the same length and width as the slot 26 in the key. Adjacent this opening two small stepped recesses 41, 42 of the same size and shape as the welding projections 27, 28 are formed in the die block. These stepped recesses are disposed at the opposite ends of the slot opening 37, as shown in Fig. 7. The bottom face of the forming punch 35 is formed or shaped in the configuration of the depression 24.

Hence when the flat section 23 of a key blank is placed over the opening 37 in the die block 34 and the punch 35 is moved down, the key blank is reformed into the shape shown in Figs. 7 and 8, the depression 24 and a center part extending between and including the welding projections 27, 28 being struck-out simultaneously. During this forming operation the downward movement of the punch is controlled to obtain the proper thickness of the bottom wall 25 and the necks 31 that connect the welding projections 27, 28 to the key blank.

After such a key forming operation, the punch 35 is withdrawn and a piercing punch 46 (Figs. 9 and 10) is driven through the reformed key blank to produce the slot 26. This punch may be used with the same die block 34 or with another similar die block to which the reformed key blank is transferred. The piercing punch is of substantially the same cross-sectional length and width as the slot opening 37 in the die block 34 and

is formed with a cutting face 47 as best shown in Figs. 9 and 10.

When the piercing punch 46 is driven down onto the reformed flat section 23 of a key blank supported on the die block 34, it cuts through the blank, in alignment with the slot opening 37 in the die block and enters this opening. This cutting action punches out from the bottom wall of the depression 24, a slug 49 which is pushed down through the slot opening in the die block and is discharged to any suitable place of deposit. This action also completes the formation of the welding projections 27, 28 by cutting the inside wall of each.

The resulting slot 26 thus formed in the key blank extends between the welding projections 27, 28 with its opposite ends disposed adjacent the projections. This completes the formation of the key which is now ready to be spot welded or otherwise secured to the can. Since the welding projections are of relatively small size with only a limited contact face in engagement with the can cover, the preferred procedure of welding is properly concentrated at the points of contact and the welding of the key is made in a minimum of time and without loss of welding energy.

It is thought that the invention and many of its attendant advantages will be understood from the foregoing description, and it will be apparent that various changes may be made in the form, construction, and arrangement of the parts and that changes may be made in the steps of the method described and their order of accomplishment without departing from the spirit and scope of the invention or sacrificing all of its material advantages, the form hereinbefore described being merely a preferred embodiment thereof.

I claim:

1. A tearing strip can opening key designed to be attached to a can by welding, said key comprising a shank having a handle at one end and an elongated depression having a relatively thin bottom wall formed in the other end, a slot in said bottom wall, and a welding projection formed integral with said bottom wall, said projection adapted to be welded to a can and to be separated from said bottom wall when the key handle is lifted to release the key.
2. A tearing strip can opening key designed to be attached to a can by welding, said key comprising a shank having a handle at one end and an elongated slot in the other end, a depression surrounding said slot, said depression having a relatively thin bottom wall, and a welding projection formed integral with said bottom wall and located contiguous an end of said slot, said bottom wall being adapted to rupture when the key handle is lifted to release the key from the projection.
3. A tearing strip can opening key adapted to be welded to a can, said key having a slot formed in one end, a depression formed in said key contiguous said slot, said depression having a relatively thin bottom wall, and a welding projection formed integral with said bottom wall, whereby when the key is lifted the bottom wall of the depression will rupture to release the key.
4. A tearing strip can opening key designed to be attached to a can by welding, said key comprising a shank having a handle at one end and an elongated thin portion in the other end, an axially aligned elongated closed slot in said elongated thin portion, and a welding projection formed integral with a portion of the wall of the slot, said portion of the wall of the slot being

adapted to rupture when the key handle is lifted to release the key from the projection.
